MEANS FOR SEPARATING FLUIDS OF DIFFERENT SPECIFIC GRAVITIES

Filed Dec. 4, 1930

UNITED STATES PATENT OFFICE

LONNIE M. JACKSON, OF COLUMBUS, OHIO

MEANS FOR SEPARATING FLUIDS OF DIFFERENT SPECIFIC GRAVITIES

Application filed December 4, 1930. Serial No. 500,117.

This invention relates to means for separation of water and other impurities from crude petroleum and products of petroleum when said petroleum and or the products thereof are of a specific gravity which is less than water or the other impurities which are desired to be removed from said crude petroleum or the products thereof.

It is a well known fact that much of the crude petroleum and the products thereof which are extracted from the continental United States have a specific gravity which is less than water; thus causing the water in the petroleum or the products thereof to settle to the bottom of a container in which said petroleum or the products thereof come to rest and are stored for a short length of time, and it is an object of this invention, working under the laws of the difference of the specific gravity of the crude or refined petroleum and water or other impurities, to devise means whereby the water will be automatically removed from the petroleum or the products thereof, said mechanism automatically expelling the water or other impurities which have a specific gravity greater than the petroleum or the products thereof and also at the same time expelling the petroleum or the products thereof through another channel and also receiving continuously a fresh supply of the unseparated petroleum or the products thereof with its impurities into the device.

Some of the objects of the invention having been stated, other objects will appear as the description proceeds when taken in connection with the accompanying drawing, in which—

Figure 1 in the drawing is a vertical cross-sectional view, taken along a vertical line through the device at approximately the center thereof.

Figure 2 is a vertical sectional view taken along the line 2 in Figure 1 thru the valve 20.

Referring more specifically to the drawing, 17 indicates a tank, preferably circular, which has a lid portion 4 with a central opening member 5a and a lid 5 for this central opening, and secured to the member 5a and the lower portion of the lid 4 are a plurality

of braces 6 which extend outwardly radially to form a reinforcement to this lid member 4. Near the top of the tank are a plurality of outlets 7. These outlets are for draining away the fluid of light specific gravity. Disposed within the tank and fitting against the inner surface thereof are a plurality of members 36, preferably circular, which are imbedded in a plurality of vertically disposed members 17, preferably of angle iron, 60 the members 36 and 16 forming a framework immediately within the tank 17. Disposed in parallel relation to members 16 are a plurality of upstanding members 16a which are connected to members 16 by a plurality of brace members 34 and 35, said members 16a flaring outwardly and upwardly at the upper end thereof, and the upper ends are secured to the upper ends of members 16, these portions serving as a cradle or support for a 70 funnel member, the upper portion of which is designated by reference character 3 and the lower portion designated by reference character 2 which funnel member immediately above the junction portions of 2 and 3 75 has a spider composed of members 10 and 10a secured therein, with a central passage-way vertically disposed therein for the reception of cylinder 9. Secured to members 16a and projecting inwardly are a plurality of projections 31 in which are fixedly secured a plurality of vertically disposed guiding members 22, there being at least four of these members 22 which are adapted to serve as a 85 track upon which float 1 moves and this float has a plurality of projections 18 secured to the exterior thereof, which are pierced by members 22 in such a manner as to allow sliding movement of members 18 on members 22.

This float member 1 comprises a rolled portion 13 at the upper end thereof and a member 13a is secured in an air tight manner to the interior side walls of float 1 by suitable means such as rivets 41, forming a compartment 13b for the reception of a buoyant fluid through valve 33 and is compartment 13b when filled entirely with a buoyant fluid such as air would be too buoyant, then a suitable heavier fluid such as oil may be injected into this compartment to impart the proper buoy-

ancy to the entire float 1. This float has a spider member composed of plurality of vanes 15 and 15a secured on the interior lower portion of float 1 and to this spider member is secured a rod 12 as at 12a, which has, on the upper end thereof, a pumping mechanism 11 composed of a plurality of cups or any other suitable pumping means which has a reciprocatory motion in cylinder 9 as the float 1 rises and falls.

10 The lower end of portion 2 has a plurality of vertically and radially disposed vanes 14 which lead to a plurality of exits 14a, so that the lower end of portion 2 being closed except for the exits 14a, the intake of the fluid into the portion 3 of the funnel will not affect unduly the action of the float because the incoming fluid will be diverted laterally through exits 14a.

15 20 Connected to the upper end of pump cylinder 9 which is supported in the hub portion formed by spiders 10 and 10a is a reducing elbow 39 to which is connected a pipe 8, which leads to a connection 38, which is connected over a hole on the inside of funnel portion 3 and over the outside surface of this hole is secured a similar member 37 to which is connected a pipe 23a, which in turn is connected to a check valve 23 and a pipe 28a leads from the lower side of said check valve to a strainer 28 in close proximity to the bottom of the tank.

25 30 To the lower end of float 1 is secured a member 19 and also a valve 20, said valve 20 having the pipe 28 connected therewith, which is connected to flexible joint 21 and pipe 21a is connected to this flexible joint, and the other end thereof is connected to flexible joint 27 which in turn is connected to pipe 40 27a, which leads into housing 30 and leading from valve housing 30 is a pipe 30a which leads to the exterior of the tank, and has a valve 32 therein with discharged pipe 30b secured at the other side of said valve 45 thereto.

50 55 Pivottally secured on member 19 as at 19a is a member 24 which has a cam surface 24a thereon, and this member 24 has a slot 24b therein and pivotally secured in the lower portion of the tank is an arm 26 which has a roller 25a at the upper end thereof adapted to have engagement with cam surface 24a and this member 26 also has a projection 26a projecting from one side thereof and along side member 24 with a pin 26b secured in said projection and projecting into slot 24b. Secured in members 26 and 24 are the pins 25b and 25d on which are secured a tension spring 25, the purpose of said tension spring to normally hold the parts in the position shown. The lower end of member 24 is adapted to slide along cam surface 26b when the roller 25a moves along cam surface 24a.

60 65 A suitable drain 29 is provided at the lower portion of the tank 17.

If desired, a suitable emulsification agent can be placed within tank 17 and also into float 1, and crude petroleum or its products or any other fluid which has a specific gravity, lighter than water, and from which foreign matter having a greater specific gravity is desired to be removed is continuously poured into intake portion 5a with lid 5 being removed, and this fluid is directed downwardly into funnel portion 3 through portion 2 and is divided into a plurality of columns by vanes 14 and is deflected laterally through exits 14a where it enters into float 1, and as tank 1 becomes filled to a predetermined degree, the foreign matter of greater specific gravity settles to the bottom of float 1, and with a proper adjustment of the buoyancy, it is intended that float 1 may be entirely filled and the fluid will continue to overflow to fill tank 17 and this weight of the float in tank 1 will not cause it to move downwardly until a predetermined amount of the foreign matter of greater specific gravity than the petroleum or products thereof, has settled in the bottom of float 1, and when this occurs, the trip joint support formed of members 24 and 26 and associated ports, will trip and float 1 will move downwardly until its bottom almost touches the bottom of tank 17, and when this occurs, valves 20 will be opened by means of the moving of pipes 20a, 21a and 27a and the matter of greater specific gravity at the bottom of float 1 will pass outwardly through pipes 30a and 30b until float 1 becomes lightened on account of the expelling of the foreign matter of heavy specific gravity, at which time the buoyancy of float 1 will cause it to again rise to the position shown in the drawing.

70 75 80 85 90 95 100 105 110 115 120 125 It might be stated that during the downward movement of float 1 that cups 11 will travel downwardly in pipe or cylinder 9. This will draw fluid from the extreme bottom of tank 17 into float 1. As it will happen that foreign matter of greater specific gravity will settle in the bottom of tank 17 by means of this arrangement, not only will the greater portion of the foreign matter be removed as the fluid passes through float 1, but any additional foreign matter which may escape through float 1 will be brought back into the float again and again, if necessary, until it is expelled from the float through the lower end thereof.

The above described operation may continue indefinitely as a constant intake may be provided. Therefore, little or no attention will be required, and a plurality of these devices may be installed separately or in series, if desired, but the main purpose of this device is to cause the fluid such as petroleum or petroleum products, to pass through the above described mechanism before it is ex- 130

elled through outlet pipes 7 into suitable storage tanks.

Members 20 and 46 are welded to opposite surfaces of tank 1 forming a coinciding opening 45 communicating with a transverse opening in which is rotatably mounted pipe 20a, said pipe 20a being plugged as at 47 at one end and having an opening 48 adapted to register with opening 45 when tank 1 is moved downwardly. Pipe 20a is held in position for rotation in casing 20 by means of a projection 49 being counter-shrunk on pipe 20a and a nut 50 being threadably secured near the end of pipe 20a.

In the drawing and specification, there has been set forth a preferred embodiment of the invention, and although specific terms have been employed, they are used in a generic and descriptive sense only, and not for purposes of limitation, the scope of the invention being set forth in the appended claims.

I claim:

1. In a device for separating liquids, a tank, a vertically slidable tank in the first tank, an air-tight compartment associated with the second tank, the second tank being open at the top, means closing the top of the first tank and projecting into the open upper end of the second tank, means for admitting a liquid through the top of the first tank and through said closing means into the second tank, a passageway leading from the bottom of the second tank to the exterior of the first tank, means for closing said passageway when the second tank is in elevated position, means for opening said passageway when the second tank is in lowered position, and means for elevating liquids from the bottom of the first tank into the said second tank.

2. In a device for separating water from petroleum and its products, a tank, a vertically slidable floating tank mounted in the first tank, buoyant means associated with the floating tank and means for regulating the buoyancy of said buoyant means, means for discharging liquid from the bottom of the floating tank when the whole of the liquid in the floating tank attains a predetermined specific gravity, said buoyant means serving to return the floating tank to normal elevated position in the said tank, and means operable by the floating tank for raising fluid from the bottom of the first tank into the floating tank.

3. In a mechanism for separating water from other liquids having a lower specific gravity than water comprising a tank adapted to be normally filled with liquid, a floating tank immersed in the first tank, means for mounting the floating tank for vertical movement within the first tank, buoyant means associated with the floating tank and means for regulating the buoyancy of the floating

tank, means for leading a liquid into the floating tank to fill the same and overflow to fill the first tank, exit means for allowing the liquid of a low specific gravity to flow from the upper portion of the first tank, means associated with the lower portion of the floating tank for draining liquid from the bottom of the floating tank to the exterior of the first tank when said floating tank sinks downwardly in the first tank due to an increase in the weight of the fluid in the full floating tank, and means for pumping fluid from the lower portion of the first tank into the floating tank when the floating tank moves downwardly in the first tank.

4. In a device for separating liquids of different specific gravities, a tank adapted to be normally filled with a liquid, a second tank mounted for vertical sliding movement in the first tank and being open at the top, an air chamber associated with the second tank, means for leading a liquid into the top of the first tank and into the second tank, means associated with the lower portion of the second tank for draining liquid therefrom when the specific gravity of the liquid in the second tank rises to a predetermined point, means for pumping liquid from the bottom of the first tank into the second tank as said second tank moves downwardly, and means for continuously expelling liquids of low specific gravity from the upper portion of the first tank.

In testimony whereof I affix my signature.

LONNIE M. JACKSON.
